UNITED STATES PATENT OFFICE.

ADOLPH M. HOLSTEIN, OF SYRACUSE, NEW YORK.

DESIGN FOR A FURNITURE, CASKET, INTERIOR, OR EXTERIOR DECORATION.

52,746.

Specification for Design.

Patented Dec. 10, 1918.

Application filed August 22, 1917. Serial No. 187,555. Term of patent 3½ years.

To all whom it may concern:

Be it known that I, ADOLPH M. HOLSTEIN, a citizen of the United States, residing at Syracuse, in the county of Onondaga and State of New York, have invented a new and original and ornamental Design for a Furniture, Casket, Interior, or Exterior Decoration, of which the following is a specification, reference being had to the accompanying drawing, forming a part hereof, which is a face view of the ornamental design.

The drawing is an elevation or face view of the design.

This design consists of crossed torch, quiver and bow entwined with a wreath of flowers, twigs, leaves and buds, bound together with ribbons terminating in a symmetrical bow knot located centrally and above the torch, quiver, bow and wreath.

I claim:

The ornamental design for a furniture, casket, interior or exterior decoration, substantially as shown and described.

In testimony whereof, I have hereunto signed my name, at Syracuse, in the county of Onondaga, and State of New York, this 29th day of June, 1917.

ADOLPH M. HOLSTEIN.
